United States Patent

Des. 240,586
Patented July 20, 1976

240,586

WAFFLE BAKER OR SIMILAR ARTICLE

Fred S. Carbon, 105 Days Ave.,
Buchanan, Mich. 49107

Filed July 24, 1974, Ser. No. 491,362

Term of patent 14 years

Int. Cl. D7—02

U.S. Cl. D7—88

Fig. 1

Fig. 2

Fig. 3

FIG. 1 is a perspective view of a waffle baker showing my new design;

FIG. 2 is a perspective view of the waffle baker as seen from the opposite side of FIG. 1; and

FIG. 3 is a top plan view.

The bottom of the waffle baker is unornamented.

I claim:

The ornamental design for a waffle baker or similar article, as shown and described.
